CAPSULE FILLING DEVICE

Arthur J. Hirschle, Springfield, Ill.

Application November 10, 1936, Serial No. 110,153

2 Claims. (Cl. 226—40)

The present invention relates to new and useful improvements in capsule filling devices and has for its primary object to provide, in a manner as hereinafter set forth, a device of this character comprising a novel construction, combination and arrangement of parts through the medium of which a large number of capsules may be expeditiously and uniformly filled by persons having little or no professional skill.

10 Another important object of the invention is to provide a device of the aforementioned character in which capsules of various sizes may be filled.

Other objects of the invention are to provide 15 a capsule filling device which will be comparatively simple in construction, strong, durable, efficient and reliable in use, compact and which may be manufactured at low cost.

All of the foregoing and still further objects 20 and advantages of the invention will become apparent from a study of the following specification, taken in connection with the accompanying drawings wherein like characters of reference designate corresponding parts throughout the several views, and wherein:—

Figure 1 is a view in top plan of a capsule filling device constructed in accordance with the present invention.

Figure 2 is a view in side elevation thereof.

30 Figure 3 is a vertical sectional view, taken substantially on the line 3—3 of Figure 1.

Figure 4 is a view in top plan of the device with the apertured top plate removed.

Figure 5 is a detail view in perspective of the 35 cover plate.

Figure 6 is a detail view in elevation of the tamper.

Referring now to the drawings in detail, it will be seen that the embodiment of the invention 40 which has been illustrated comprises an annular supporting base 1 having an external flange 2 on its lower end. The upper portion of the supporting base 1 is enlarged and externally threaded, as at 3.

45 Threadedly mounted for vertical adjustment on the annular supporting base 1 is a ring 4 which supports a removable plate 5. The plate 5 has formed therein openings 6 for the reception of the capsules 7. As illustrated to advantage 50 in Figure 1 of the drawings, the openings 6 in the plate 5 are preferably formed in groups of different sizes. It may be well to here state that a plurality of the plates 5, having different sizes of openings 6 therein, may be provided.

55 Mounted on the upper end of the supporting

base 1, within the ring 4, is a disk 8 which constitutes a table for supporting the capsules 7, as best seen in Figure 3 of the drawings. Projecting from the periphery of the table 8 are lugs 9 which are slidably engaged in vertical grooves 10 which are formed in diametrically opposite sides of the ring 4 for connecting said table to said ring for rotation therewith.

From a consideration of the foregoing, it is thought that the manner of using the device will be obvious, particularly to those skilled in the art to which the invention pertains. The device is assembled and the capsules 7 are inserted in the openings 6, said capsules resting on the table 8. The ring 4 is then adjusted on the supporting base 1 to bring the plate 5 substantially flush with the tops of the capsules. The substance (not shown) is then placed on the plate 5 and swept into the capsules. Of course, any other procedure may be followed for placing the substance in the capsules. After the capsules have been filled and tamped, the ring 4 is adjusted downwardly on the annular base 1, thus lowering the plate 5 and causing the capsules 7 to project thereabove. The capsules may then be conveniently closed or capped after which said plate 5 with the filled and capped capsules suspended in the openings 6 thereof may be removed. It will be readily apparent that by simply raising or lowering the ring 4, with the plate 5 thereon, capsules of various lengths may be accommodated.

In Figure 5 of the drawings the reference numeral 11 designates a substantially flat, angular plate which may be used to cover certain of the openings 6 in the plate 5 when all of said openings are not to be used. The element 11 may also be used for transferring the substance with which the capsules are to be filled to the retaining plate 5.

Figure 6 of the drawings illustrates a tamper 40 12 which includes a polygonal body 13 from the sides of which various sizes of fingers 14 project. The fingers 14 are engageable in the different sizes of capsules which are filled for packing the substance which has been placed in said capsules. 45

It is believed that the many advantages of a capsule filling device constructed in accordance with the present invention will be readily understood and although a preferred embodiment of the invention is as illustrated and described, it 50 is to be understood that changes in the details of construction and in the combination and arrangement of parts may be resorted to which will fall within the scope of the invention as claimed.

What is claimed is:—

1. A capsule filling device comprising a supporting base, a ring threadedly mounted for vertical adjustment on the supporting base, said ring having vertical grooves in its inner periphery, a plate removably mounted on the ring, said plate having openings therein for the reception of the capsules, a table mounted on the base within the ring for supporting the capsules, and lugs on the table engaged in the grooves for connecting the table to the ring for rotation therewith.
- 5 2. A capsule filling device comprising an annular supporting base including an externally

threaded upper portion, a ring threaded mounted for vertical adjustment on the base, said ring having vertical grooves in diametrically opposite sides of its inner periphery, a removable plate mounted on the ring, said plate having openings therein for the reception of the capsules, a table mounted on the upper end of the supporting base within the ring for supporting the capsules, and lugs projecting from the edge of the table and slidably engaged in the grooves for connecting 10 said table to the ring for rotation therewith.

ARTHUR J. HIRSCHLE.
